Patented Dec. 13, 1927.

UNITED STATES PATENT OFFICE.

CHARLES B. WATERS, OF MONTCLAIR, NEW JERSEY.

DESIGN FOR A WATER-HEATER CASING.

Application filed July 10, 1926. Serial No. 18,307. Term of patent 14 years.

To all whom it may concern:

Be it known that I, CHARLES B. WATERS, a citizen of the United States, residing at Montclair, in the county of Essex and State of New Jersey, have invented a new, original, and ornamental Design for Water-Heater Casing, of which the following is a specification, reference being had to the accompanying drawing, forming part thereof.

The figure is a perspective view looking downward on a heater showing my new design.

I claim:

The ornamental design for a water heater casing as shown.

CHARLES B. WATERS.
